DOOR LOCKING AND SEALING ARRANGEMENT
Harold J. Carlson, Lakeside, Mich., and Roland J. Olander, La Grange, Ill., assignors to W. H. Miner, Inc., Chicago, Ill., a corporation of Delaware
Filed Sept. 3, 1964, Ser. No. 394,282
9 Claims. (Cl. 292—196)

This invention relates in general to railway car locking devices and more particularly to a locking or latching arrangement for use in a plural or multiple freight car.

For ease in loading freight cars with certain types of freight, such as lumber, for instance, it is desirable that the car sides be composed of enough doors to provide loading openings at various positions along the side of the car which are equivalent to one-half the car length. For instance, a 48-foot car could be provided with six 8-foot doors. The doors are slideable or movable along the side of the car and are adapted to be slid into an overlapping relationship with each other. Although such all-door structural arrangements permit wide openings to be provided in the sides of the car for loading purposes, several inherent problems are presented with respect to locking the doors after same are closed. Thus, in cars having four or six doors on a side, each door might be locked by its own locking arrangement, but this in turn is a wasteful and uneconomic procedure. In addition, if the doors are not rigidly held with respect to each other, the vibrational and other stresses set up during movement of the car tend to loosen the doors.

The present invention provides a solution for these problems in a simple and unique manner. Thus, in a freight car having four doors on a side with one pair being slideable on one track and the other pair slideable on a track extending parallel thereto, a single locking assembly is utilized for locking all of the doors into a rigid assembly. This is done by providing an elongated lock and seal member rotatably mounted on one door about an axis offset from the plane of the doors and adapted, after locking of the mechanism, to be wedged against the edge juncture of both pair of doors to rigidly hold the doors in their closed positions.

It is therefore a primary object of the present invention to provide an improved locking and sealing arrangement for a plural or multiple door freight car.

It is another object of the present invention to provide a single locking assembly for a multiple door freight car.

It is another object of the present invention to provide a locking arrangement for more rigidly securing all of the doors of a multiple door freight car relative to one another when closed and also to provide an effective seal therebetween.

Other objects of this invention will become apparent on examination of the following specification, claims and drawings, wherein:

FIG. 1 is a general elevational view of the four doors of a freight car which define the side thereof with the doors shown broken along their vertical axes and locked in their closed positions by the novel locking assembly of this invention;

FIG. 2 is a top plan view of the doors shown in FIG. 1 showing the offset relationship between the two pair of doors and the locking assembly operable therebetween;

FIG. 3 is an enlarged scale vertically broken elevational view illustrating the locking assembly in greater detail;

FIG. 4 is an enlarged scale horizontal section of the locking assembly in its locked condition taken generally along line 4—4 of FIG. 3; and

FIG. 5 is a horizontal section similar to FIG. 4 of the locking assembly in its unlocked condition.

2

In FIG. 1 of the drawings a group of doors 10, 12, 14 and 16 are shown with the doors broken along their longitudinal vertical axes. The doors form the side of an all-door freight or commodity car with the doors 10 and 12 being slideable together or separately along one linear path and the doors 14 and 16 being slideable in another linear path spaced from but extending parallel to the one linear path. As is well known in the art, freight car doors such as those shown in the drawings are longitudinally slideable between fixed vertical end structure at opposite ends of the car. As the fixed end structure, the specific rail or track structure at the upper and lower edges of the doors 10, 12, 14 and 16, and any roller arrangement for supporting the doors therefrom or thereon constitute no part of the present invention, same are not shown in detail in the drawings. However, in FIG. 1, rollers 18 of the type that may be raised after movement of the doors into desired positions are shown somewhat diagrammatically at the lower edges of the doors. For the purposes of the invention, it is only of importance to note, as shown in FIG. 2, that the pair of doors 14 and 16 are slideable along a linear path which is offset or spaced inwardly or rearwardly of, but parallel to, a linear path along which the pair of doors 10 and 12 are slideable. The doors are thus arranged in pairs with any door being adapted to be moved along its trackway into either a tandem or overlapping relationship with the doors of the other pair. This will either close the car or provide an opening of desired size and at a desired location therein. When closed, the doors 12 and 14 form an edge juncture at the longitudinal center of the car in which their edges are adjoining but offset as seen in FIG. 2 and they, together with doors 10 and 16, are adapted to be locked in position by a novel locking and sealing assembly 20.

The locking and sealing assembly 20 comprises an elongated vertically arranged lock bar or rod 22 rotatably supported in hinges or brackets 24. A handle member 26 is rigidly fixed to the bar 22 for the purpose of manually rotating the bar in the brackets 24. The handle is adapted to be rotated against the wall of door 12 where it may be held in that position by a clip 28.

The brackets 24 are fastened on one leg 30 of an L-shaped metal plate 32 mounted on the door 12. The other leg 34 of the plate 32 abuts the right vertical edge of the door 12 adjacent door 14 as seen in FIGS. 4 and 5. Similar plates 36 are provided for the other edges of door 12 and for the edges of the other doors for the purpose of protection. A series of spaced apart hinges 38 are carried by the door 12 adjacent the leg 34 of plate 32 and each hinge has a mounting flange 40 extending through openings or notches in the leg 34 to permit the hinges 38 to be supported at respective positions on the door 12.

The hinges 38 are provided with bifurcations 42 as seen in FIG. 3 and a hinge butt 44 is rotatably supported between the bifurcations 42 by means of a pin 46. Both the hinges 38 and the hinge butts 44 have a generally circular periphery and nest in a correspondingly shaped portion 48 of a J-shaped lock and seal member 50 which is also characterized by an elongated sealing arm 54. The hinge butts 44 have slightly larger diameters than the bifurcations 42 and are welded, at 52 for example, in FIGS. 4 and 5, to the inner wall of the J-shaped portion 48 so that the lock and seal member 50 is rotatably supported on the hinges 38.

It will be noted that the hinges 38 project slightly outwardly of the plane of the door 12 so that the axis of rotation 53 of the hinge butts 44 and the lock and seal member 50 is offset outwardly of door 12. Therefore, any movement of the door 12 to the right, as seen in the drawings, tends to force the elongated sealing arm 54 of the member 50 even more tightly against the edge of the

door 14 when the lock and seal member 50 is in its locked position, as will be described.

The lock and seal member 50 extends practically the full height of the doors and the outer surface 55 (FIGS. 4 and 5) of its J-shaped portion 48 has a series of spaced apart flange-like bosses 56 mounted thereon. Each flange-like boss 56 is nested between the legs 58 at one end of an operating link 60. Each link 60 is rotatably connected to the respective boss 56 by a pin 62 and each has a somewhat arcuate configuration with its other end terminating in a pair of spaced apart legs 64. One end of an operating lever 66 is rotatably supported between the legs 64 by means of a pin 68 and the other end of the operating lever is fastened to the lock bar 22 by welds 70 (FIGS. 4 and 5), for example.

To open the lock assembly 20, the handle 26 is rotated outwardly from the door 12 to in turn rotate the lock bar 22 in a counterclockwise direction. The operating levers 66 are also rotated counterclockwise and they carry the operating links 60 to the right as viewed in FIGS. 4 and 5. The force of this movement is transmitted through the pins 62 and the bosses 56 to rotate the elongated lock and seal member 50 counterclockwise about its axis of rotation 53 and to bring the elongated sealing arm 54 of the lock member 50 out of engagement with the edge of the door 14 and into engagement with the inner surface of the door 12 as seen in FIG. 5. The arm 54 is normally held in this position against the door 12 with any forces tending to rotate the member 50 about axis 53 being transmitted through pin 62 and link 60 to pin 68. Since a component of this force is transmitted along a radial line 72 extending from the axis of rotation of the lock bar 22, rotation about the lock bar 22 is resisted and therefore rotation of the lock member 50 is also resisted. The doors 10, 12, 14 and 16 may therefore be moved freely and doors 10 and 12 can be moved into overlapping relationship with doors 14 and 16 or vice versa as needed for loading.

In order to lock the side of the car, the respective doors 10, 12, 14 and 16 are aligned in tandem relationship with the edges of doors 12 and 14 in adjoining but offset relationship. The handle 26 is then rotated clockwise, approximately 180°, into a position against the outer wall of the door 12 and into engagement with the clip 28. The lock bar 22 therefore rotates in the same direction 45 to carry the lever 66 therewith. The operating link 60 follows this movement while swinging the lock member 50 in a clockwise direction about its axis of rotation 53. The lock member 50 thus swings through approximately 90° until its elongated sealing arm 54 abuts the edge of 50 door 14 with further movement serving to wedge the doors 14 and 16 together against the right side of the car frame and the doors 10 and 12 against the left side of the car frame. Although the end of the J-shaped portion 48 of the lock and seal member 50 tightly abuts the outer surface of the plate 32 on the door 12 as shown in FIG. 4 to complete the seal between the offset adjacent edges of the doors 12 and 14, it is to be understood that the invention is not to be limited to this specific structural arrangement.

While the lock member 50 moves through 90° during locking of same, the pin 68 is carried over an arc of greater magnitude, as may be seen by comparison of FIGS. 4 and 5, to a position behind the lock bar 22 and adjacent the plate 32. The radial line 72 on which pin 68 rotates about bar 22 is transferred from a position generally parallel to a radial line 74 extending from pin 62 to the axis 53, as seen in FIG. 5, to a position where the radial lines 72 and 74 are adapted to intersect at a juncture 75 (FIG. 4) lying between the lock bar 22 and the lock member 50. This thus provides an overcenter locking arrangement.

Thus, if force should be exerted to move the doors 10 and 12 to the right, this tends to rotate the lock member 50 counterclockwise about the axis 53 wedging the elongated arm 54 more tightly against the door 14 to rigidify the assembly while the back pressure is also transmitted through the hinges 38 to resist movement of the door 12. If the doors 14 and 16 should tend to move to the left, the force exerted against arm 54 is transmitted through pin 62 and link 60 to the pin 68 and since that force either tends to pull the pin 68 along its radial line 72 or to rotate the pin clockwise about bar 22, considerable resistance to further movement of the doors is also encountered.

It is noted that the foregoing structural arrangement permits the locking and sealing of one side of an "all door" freight car having multiple doors by means of a single locking and sealing assembly of the type shown and described.

The foregoing is a description of one embodiment of an improved lock and seal assembly for a plural door freight car, the inventive concepts of which are believed more fully set forth in the appended claims.

What is claimed as new is:

1. In a lock and seal assembly for use on a plural door freight car in which one pair of doors is arranged for movement along one trackway and another pair of doors is arranged for movement along another trackway offset from said one trackway and in which said doors are in a generally tandem arrangement when closed with adjacent vertical edges of one door of each pair in adjacent but offset positions, the improvement comprising a lock and seal member which extends the full length of the doors and which is rotatably carried by one of said doors adjacent one of said edges, said lock and seal member being adapted to engage the adjacent edge of the other door along its length when rotated in one direction for forcing said doors in opposite directions and being adapted to be arranged in a generally parallel position to said doors when rotated in the opposite direction to permit free movement of all of said doors, means for rotating said lock and seal member in opposite directions, and means operable in response to the engagement of said lock and seal member with said other door for preventing inadvertent disengagement of said assembly.

2. The assembly claimed in claim 1 in which said means for preventing disengagement comprises a first pin carried by said lock and seal member for rotation about the axis of rotation of said member, a second pin rotatable about an axis offset from said first pin, and an operating link rotatably connected between both of said pins.

3. The assembly claimed in claim 2 in which said second pin is rotatable about said offset axis through an arc greater than the arc through which said lock and seal member is rotatable whereby said second pin is positioned so that forces transmitted to said lock and seal member from said doors are adapted to act along the radial line from said offset axis.

4. In the assembly in claim 2, said rotating means comprising a lock bar rotatably carried by said one door coaxially with said offset axis and carrying said second pin for rotation about said offset axis whereby to rotate said lock and seal member in opposite directions.

5. In a lock and seal assembly for use on a plural door freight car in which one door is arranged for movement along one trackway and another door is arranged for movement along another trackway extending parallel to but offset from said one trackway and in which said doors are in a generally tandem arrangement when closed with adjacent vertical edges thereof being offset from each other, the improvement comprising a lock and seal member rotatably carried by one door adjacent one of said vertical edges, a vertically elongated arm on said lock member adapted to engage substantially the full length of the adjacent offset edge when said lock and seal member is rotated in one direction for applying a force against said offset edge to force said doors in opposite directions along the respective trackways, and means for manually

rotating said lock and seal member in either said one direction to engage said elongated arm against said adjacent offset edge or in the opposite direction to position said elongated arm generally parallel to said one door so as to permit free movement of all doors, said means being characterized by an over-center locking arrangement which prevents inadvertent disengagement of said elongated arm from said offset arm.

6. In a lock and seal assembly for use on a freight car having a plurality of movable doors with one door adapted to have one edge aligned adjacent to the edge of another door and offset from said other door, the improvement comprising a lock bar rotatably carried by said one door, a plurality of spaced apart hinges projecting from said one door, a lock and seal member rotatably carried by 15 said hinges for rotation on a vertical axis offset outwardly of said one door and having an elongated arm extending substantially the full height of said doors, an operating link pivotally mounted at one end on said lock and seal member, an operating lever carried by said lock bar for 20 rotation therewith, and means pivotally connecting the other end of said operating link to said operating lever whereby rotation of said lock bar in one direction rotates said elongated arm of said lock and seal member into locking and sealing engagement with the edge of said other door.

7. In a lock and seal assembly for use on a freight car having a plurality of movable doors arranged to form one side of said car with one door adapted to have one edge aligned adjacent to the edge of another door and offset 30 from said other door when said doors are closed to form said side, the improvement comprising a lock bar rotatably carried by said one door, a lock and seal member carried for rotation about a vertical axis by said one door and having an elongated arm extending substantially the 35 full height of said doors, said axis being offset outwardly from said one door and lying generally between said adjacent edges of said doors, and means pivotally connected between said lock bar and said lock and seal member for transmitting the rotation of said bar in one direction into rotation of said elongated arm on said lock and seal member into locking and sealing engagement with the said adjacent offset edges of said doors.

8. In a lock and seal assembly for use on a freight car having a plurality of movable doors with one door adapted to have one edge aligned adjacent to the edge of another door and offset from said other door, the improvement comprising a lock bar rotatably carried by said one door, a vertically extending lock and seal member having a 45 height corresponding to that of the doors and being J-shaped in horizontal cross section, a plurality of spaced hinge arms mounted on said one door with each hinge arm

carrying a hinge butt for rotation about an axis offset outwardly from said one door and lying generally between said adjacent edges of said doors, said hinge butts being fixedly nested in the arcuate portion of said J-shaped lock and seal member, an operating link pivotally mounted on said lock and seal member, and an operating lever pivotally connected between said lock bar and said operating link in a manner such that rotation of said lock bar in one direction rotates the non-arcuate portion of said J-shaped lock and seal member into sealing engagement with the edge of said other door, said sealing engagement being retained by an over-center lock defined by said pivotally connected elements.

9. In a lock and seal assembly for use on a multiple door freight car in which one pair of doors is arranged in tandem for movement along one trackway and another pair of doors is arranged in tandem for movement along another trackway parallel to but offset from said one trackway and in which all of said doors are in a generally tandem arrangement when closed to form one side of said car with vertical edges of one door of each pair being disposed in adjacent but offset positions, the improvement comprising a single rotatable lock member carried adjacent one of said vertical edges for applying forces against said offset edges in opposite directions to force said pairs of doors along their respective trackways in opposite directions when said lock member is rotated in one direction to engage the adjacent offset vertical edge, said lock member being vertically elongated and extending a distance corresponding to the height of said doors whereby to provide a seal between said offset door edges along the full height thereof, and means coupled to said member for resisting inadvertent rotation of said lock member in an opposite direction when said lock member is engaged with said adjacent offset vertical edge.
